LINUS P. CLAWSON, JOHN A. KELLER, AND JAMES W. SEE, OF HAMILTON, OHIO, ASSIGNORS TO THE BLACK & CLAWSON COMPANY, OF SAME PLACE.

MECHANISM FOR TRANSMITTING MOTION.

SPECIFICATION forming part of Letters Patent No. 392,782, dated November 13, 1888.

Application filed July 21, 1888. Serial No. 280,607. (No model.)

To all whom it may concern:

Be it known that we, LINUS P. CLAWSON, JOHN A. KELLER, and JAMES W. SEE, of Hamilton, Butler county, Ohio, have invented certain new and useful Improvements in Mechanism for Transmitting Motion, of which the following is a specification.

This invention pertains to mechanism for transmitting motion, and relates particularly to a device for transmitting rotary motion to two shafts in such manner that the rotary force will be transmitted equally to the two shafts, while the velocity of rotation of the two shafts may vary with reference to each other, according to the degree of resistance offered to the rotation of the individual shafts.

An example of the utility of our mechanism may be found in machines for winding paper. Assume a roll of wide paper to be slit into two narrower webs and wound into rolls. The wide web of paper is usually carried over the slitters, and the resulting two continuous narrower webs go to two spindles which wind them into rolls. The motion of the paper is generally produced by the winding up of the two narrower webs, the pull thus produced on the paper causing the paper to unroll from the initial roll and to properly pass through the slitters. It is obvious that the paper will be wound up faster as the diameter of the rolls increases, the unwinding from the initial roll becoming of course correspondingly more rapid. So long as both of the narrow rolls maintain precisely equal diameters the strains upon the two narrow webs will of course be the same; but one of the rolls is liable to increase in diameter faster than the other, and consequently the larger roll of the two, both being driven positively at the same rate of speed, would determine the velocity with which the paper is unwound from the initial roll and pulled through the slitters. It is obvious that the smaller roll of the pair will in such case be unable to wind up its web as fast as supplied. Furthermore, one of the webs of paper is liable to be broken, and, in case the other web continues to wind up, one of the webs becomes disordered and often largely wasted. Winding-machines are often arranged to drive

through the medium of friction in such manner that the roll under greatest strain will slacken its velocity, so that the several webs are kept at equal tautness. Sometimes winding devices are operated through the medium of compensating gearing in such manner that the velocities of rotation of the several winding-spindles apportion themselves to the strain imposed upon them by the pull of the web which they wind. Winders thus arranged with compensating gears have heretofore involved a multiplicity of shafts—that is to say, a greater number of shafts than there were winding-spindles.

Our invention involves a compensating-gearing system, but necessitates the use of no more shafts than there are winding-spindles—that is to say, if we wish to produce the motions for two winding-shafts we involve no intermediate shaft.

We illustrate our invention in connection with a mechanism adapted to transmit motion to a two-spindle winder.

Our improvements will be readily understood from the following description, taken in connection with the accompanying drawings, in which—

Figure 1 is a plan of a transmitting mechanism arranged to transmit motion to two winding-spindles, much of the mechanism appearing in horizontal section upon the line *a a* of Fig. 2; Fig. 2, a side elevation of the pulley D; Fig. 3, a sectional plan of the pulley D and its immediate accessories, the section being taken upon the line *b b* of Fig. 2; and Fig. 4, a diametrical section of the pulley D in the same plane as the section in Fig. 1, this view representing the gearing in modified but equivalent form.

In the drawings, A represents frame-work for the support of two rotary shafts; B, one of the shafts to which rotary motion is transmitted, this shaft being illustrated as provided upon one of its ends with a squared portion to engage the usual square socket in the end of a removable winding-spindle; C, a second similar shaft arranged parallel with the first one and intended to be rotated in the same direction; D, a pulley loose on the shaft B and in

tended to receive the driving-belt for transmitting rotary motion to the apparatus; E, a gear fast on the shaft B; F, a planet-spindle housed in the pulley D parallel with the shaft 5 B; G, a broad pinion on this spindle, this pinion gearing with the gear E; H, a gear loose upon the shaft B and similar in size to the gear E; J, a sprocket-gear united to the gear H and arranged to revolve with it; K, a sprocket-10 gear fast on the shaft C; L, a chain belt transmitting motion from the sprocket-gear J to the sprocket-gear K; M, a second planet-spindle journaled in the pulley D parallel with the planet-spindle F; N, a pinion fast upon one 15 end of this second planet-spindle, this pinion gearing into the pinion G, but not gearing into the gear E, and P, a similar pinion fast upon the opposite end of the second planetary spindle, M, and gearing into the gear H.

20 Assume for the time being, in connection with Fig. 1, that pinions G and P are both fast upon spindle F and that the spindle is free to revolve in its bearing in the pulley. Under such circumstances it is obvious that if rotary 25 motion be transmitted to the pulley it will revolve freely upon the shaft B and that no motion will be transmitted to the shaft or to gears E and H by reason of the fact that the assumed planetary spindle and its two pinions would 30 be at liberty to freely rotate during their planetary travel. Under the assumed construction the device would therefore be inoperative; but let it be observed that the pinions G and P are upon two separate spindles and that these two 35 spindles are geared together by the pinions G and N. Now, when we revolve pulley D the tendency of the planetary work to free rotation is met by the condition that the two planet systems must revolve in opposite directions 40 during the planetary travel. As the two planet systems are geared together, they cannot rotate in the same direction. It follows that as the pulley D rotates the two planet systems practically locked together act as dogs, 45 tending to drag the gears E and H around and compel them to partake of the same rotation as the pulley D. Under such circumstances the two gears E and H will rotate as fast as the pulley D, and the gear E being fast on shaft B 50 will rotate that shaft, and the gear H will transmit motion to the shaft C through the medium of the sprocket-gears J and K and the belt L. Under these conditions the two shafts B and C will be driven at the same 55 speed as the pulley D, and the planetary system would be acting merely as a driving-dog. Now, however, assume that some extraordinary resistance were offered to the rotation of the shaft B. Assume that it were 60 even absolutely locked against rotation. Now, when pulley D rotates the pinion G is forced into rotation by its engagement with the then stationary gear E. The pinion G, gearing with the pinion N, transmits rotary motion to 65 planet-spindle M, and thence to the pinion P, which causes rotation of gear H and ultimately of shaft C. By analyzing the resultant veloci-

ty it will be found that the shaft C will revolve at twice the speed of pulley D. Briefly, rotary motion having been suppressed in shaft 70 B, all of the rotation becomes transmitted to shaft C. If, instead of assuming absolute non-rotation of shaft B, we assume such a resistance as will permit of slow rotation, then we will find both shafts B and C revolving at 75 speeds inversely proportionate to the resistance which they offer to rotation. Therefore, if both shafts are operating winding-spindles they will perform the winding with equal force, and if the weight of one of the winding-spindles becomes increased over the other the second spindle will increase its speed of rotation, while the first one slackens its speed, thus equalizing the winding strains. If one web 80 of paper being wound should become accidentally or intentionally broken, then the winding strain will be imposed entirely upon the second winding-spindle, and under these conditions the second winding-spindle will cease to rotate and the first winding-spindle 85 will rotate with great rapidity, no winding of course being done under such conditions by reason of the fact that the spindle connected with the paper does not rotate and the one that does all of the rotating has no connection 90 with the paper.

In Fig. 1 it should be observed that pinion G is a mere idle-pinion, serving to transmit motion between pinion N and gear E and to properly change the direction of motion. It 95 is therefore immaterial whether planet-spindle F is fast in its pinion and loose in its bearings or whether it is a mere fixed stud on which the pinion G may loosely rotate.

It was shown in a hypothetical case above 100 given that if pinions G and P, engaging gears E and H, as in Fig. 1, were both fast on one planet-spindle the device would be inoperative. Employing pinion G as a mere idle-pinion to reverse the direction of motion effects, 105 at once, changes in the character of the device, and any equivalent system of gearing introduced between gear E and the spindle of pinion P will produce the same effect. An equivalent is shown in Fig. 4, in which a sprocket-wheel, Q, takes the place of gear E, sprocket-pinion R takes the place of pinion N, and chain belt S takes the place of idle-pinion G, the effect of the transmission and reversion of matters being precisely the same, while sprocket- 115 and-chain gearing is a well-known substitute for toothed gearing. Other well-known equivalent gearing may also be used instead of 120 chain-gearing for transmitting motion from gear H to shaft C.

125 We claim as our invention—

In mechanism for transmitting motion, the combination, substantially as set forth, of two parallel rotary shafts, B and C, a pulley loose on shaft B, two gears upon shaft B, one loose 130 and one tight thereon, means for transmitting rotary motion from the loose one of said gears to said shaft C, a planet-spindle journaled in said pulley, a pinion on one end of said plan-

et-spindle gearing with one of said gears on shaft B, and gearing connecting the other end of said planet-spindle with the other of said gears on shaft B in such manner that the motion effects are reversed at the two ends of said planet-spindle, whereby when said pulley rotates on shaft B one gear on shaft B tends to urge the planet-spindle into rotation

in one direction and the other of said gears tends to resist such rotation.
